UNITED STATES PATENT OFFICE.

FRANK A. MISSMAN, OF LOS ANGELES, CALIFORNIA, ASSIGNOR OF ONE-HALF TO MERCHANTS FIRE DISPATCH, INC., OF LOS ANGELES, CALIFORNIA, A CORPORATION OF CALIFORNIA.

WATCHMAN'S TIME-RECORDING CLOCK.

Application filed November 13, 1924. Serial No 749,682.

My invention relates to time recording clocks of the character embodied in my co-pending application Serial No. 749,681, filed Nov. 13, 1924, and more particularly, although not necessarily, to time recording clocks for use by watchmen.

It is a purpose of my invention to provide a time recording clock including a dial movable by suitable clock mechanism, and 10 extremely simple, inexpensive and durable means for punching the dial, such means being manually operable by the watchman or operator and in such manner as to prevent the possibility of tampering with or 15 injuring the elements comprised in such means.

It is also a purpose of my invention to provide a clock of the above described character in which the dial, operating mechanism therefor, and the said punching means 20 are accessible only through the opening of a door on the casing, and a second punching instrument operable upon opening the door whereby the record of such fact is 25 made upon the dial.

I will describe only one form of time recording clock embodying my invention, and will then point out the novel features thereof in claims.

30 In the drawings,

Figure 1 is a view showing in front elevation, with portions thereof broken away and other portions in section, one form of time recording clock embodying my invention;

35 Figure 2 is an enlarged plan view showing the mechanism for actuating one of the punching instruments embodied in the clock shown in Figure 1;

40 Figures 3 and 4 are sectional views taken on the lines 3—3 and 4—4, respectively, of Figure 1.

45 Referring specifically to the drawings, in which similar reference characters refer to similar parts in each of the views, my invention, in its present embodiment, comprises a casing 15 provided with a door 16 having a transparent panel 17 through which certain of the contents of the casing 50 can be readily viewed. The casing in the present instance is of circular form, and

mounted axially thereof is a shaft 18 to which is fixed a dial 19 adapted to be continuously rotated in a clockwise direction by means of suitable clock mechanism. As 55 this clock mechanism is conventional, it has not been shown. The dial 19 is provided with radial graduations, certain of which are numbered to designate the twenty-four hours of a day, while the intervening graduations designate fractions of the hours. The dial 19 is preferably formed of paper or other material which is capable of being readily perforated.

As illustrated to advantage in Figures 2 65 and 3, a U-shaped frame 20 is secured at its ends in horizontal position within the casing 15, and to the intermediate portion of this frame is secured a metallic body 21 by means of screws 22. One of the screws extends through the frame and body and also through an L-shaped yoke 23, the vertical portion of which provides a limiting or keeper arm 24 provided with openings 25 and 26. The arm 24 is disposed in spaced 70 parallel relation to the lower side of the body 21 so as to accommodate and permit unrestricted movement of the dial 19 therethrough.

A punching instrument 27 is mounted for 80 sliding movement within frame 20 and the body 21, and this instrument is provided with a recessed end to form divergent blades 27^a which, on the movement of the instrument through the dial, forms a clean perforation in the dial. The inner end of the instrument 27 is formed with an up-turned hook 28 engaged by a crank 29 secured to a shaft 30 journaled in the parallel portions of the frame 20 and provided at one end 85 with an angular extension 31 which is connected to a spring 32 for normally urging the shaft to a position in which the instrument 27 occupies an inactive or non-punching position, as illustrated in Figure 3. The 90 opposite end of the shaft 30 is bent to provide an angularly disposed arm 33 provided with a flattened end 34 disposed in partly spanning relation to the inner end of a sleeve 35 fixed to and extending through 100 the periphery of the casing 15.

A key 36 is adapted to be inserted into

the sleeve 35, and when forced inwardly engages the flattened end 34 to move the arm 33, and consequently the shaft 30, to actuate the crank 29 in moving the instrument 5 27 forwardly to active position in which the bladed end 27^a pierces the dial 19 and reposes within the opening 26 of the arm 24. It is to be noted that the position of the flattened end 34 with respect to the 10 sleeve 35 is such that when forcing the key inwardly it will ride off of the flattened end, owing to the turning movement of the arm 33 so that the possibility of bending, distorting or in any way injuring the key, 15 arm or the mechanism operated by the arm is prevented. The key 36 is constructed to provide a shoulder 37 which is adapted to engage the outer end of the sleeve 35 so as to limit the inward movement of the key. 20 For the purpose of recording the surreptitious opening of the door, should anyone attempt to alter the true record made on the dial by the punching instrument 27, I have provided a second punching instrument 38, 25 which is mounted for sliding movement in the frame 20 and the body 21 above the punching instrument 27, and in such manner as to pierce the dial 19 when moved forwardly from the position shown in Figure 3. This instrument is provided with a cutting end identical to the end 27^a of the instrument 27, and its inner end is provided with a downwardly turned hook 39 engaged by a crank 40 fixed to a shaft 41, journaled 30 in the frame 20 and bent at one end to provide an angularly disposed arm 42, which at all times engages an arm 43 fixed to a locking spindle 44. A spring 45 normally urges the shaft to a position in which the 35 punching instrument 38 occupies the inactive position shown in Figure 3, and the arm 42 into engagement with the arm 43.

The locking spindle 44 is rotatably mounted in a sleeve 46 extending through the periphery of the casing 15. The locking spindle 44 is flattened adjacent one end to provide a rotatable locking bolt 47 which is adapted to be engaged by a keeper 48 fixed to the door 16. The sleeve 46 is slotted at 45 two points as indicated at 44^a to receive the keeper 48 and to permit the lock bolt 47 to engage the keeper and thus secure the door in closed position. The angular end 49 of the spindle 44 provides means by which 50 a key 50 can rotate the spindle to move the lock bolt 47 to locking or releasing position with respect to the keeper 48. Through the medium of the arms 42 and 43, the spring 45 functions to normally urge the 55 spindle 44 to a position in which the lock bolt 47 engages the keeper to prevent the opening of the door. However, when the spindle is rotated through the medium of the key 50 to move the bolt 47 to releasing 60 position with respect to keeper, the arm 43

is moved to actuate the arm 42 and thus rotate the shaft against the tension of the spring 45 to shift the punching instrument 38 from active to inactive position, thereby effecting a perforation of the dial 19 and 70 thus recording the fact that the lock has been actuated and the door opened.

In practice, the dial 19 is adapted to be punched at prearranged intervals by the watchman through the use of the key 36 75 to operate the punching instrument 27 in the manner previously described whereby the perforation formed in the dial as the result of this operation makes a permanent record on the dial. Should the watchman 80 attempt to tamper with any of the mechanism for actuating the dial or the punching instrument, it will be manifest from the preceding description that upon opening of the door 16 the dial will be perforated by 85 the punching instrument 38 to record the fact.

Although I have herein shown and described only one form of time recording clock embodying my invention, it is to be 90 noted that various changes and modifications may be made without departing from the spirit of my invention and the spirit and scope of the appended claims.

I claim as my invention:

1. A time recording clock comprising a casing, a dial movable in the casing, a perforating instrument movable in the casing to perforate the dial, a shaft operatively connected to the instrument and movable 100 to actuate the latter, means for yieldably urging the shaft to a position in which the instrument occupies non-perforating position, an angularly disposed arm on the shaft, and a sleeve extending through the casing 105 to permit the insertion of a key into the casing and into engagement with said arm in a manner to actuate the shaft for operating the instrument and perforating the dial.

2. A time recording clock comprising a 110 casing, a dial movable in the casing, a perforating instrument in the casing for perforating the dial, a shaft operatively connected to the instrument, means for yieldably urging the shaft to a position in which 115 the instrument occupies a non-perforating position with respect to the dial, said casing being formed with an opening, and an angular extension on the shaft disposed adjacent said opening whereby a key inserted 120 in the opening will engage the extension and turn the shaft to move the instrument to perforating position against the action of said urging means.

3. A time recording clock comprising a 125 casing, a dial movable in the casing, a perforating instrument in the casing for perforating the dial, a shaft operatively connected to the instrument, means for yieldably urging the shaft to a position in which 130

the instrument occupies a non-perforating position with respect to the dial, a sleeve extending through and fixed in the casing, an extension on the shaft having its free end in spanning relation to the inner end of the sleeve so that when a key is inserted into the sleeve the extension will be engaged to actuate the shaft and move the instrument to perforating position, and under movement of the shaft the extension will be moved out of the path of movement of the key for the purpose described.

FRANK A. MISSMAN.
